DEVICE FOR SAMPLING FLUID MATERIALS

Filed Aug. 30, 1949

UNITED STATES PATENT OFFICE

2,564,697

DEVICE FOR SAMPLING FLUID MATERIALS

Addison W. Kelley, Conestoga Township, Lancaster County, Pa., assignor to Armstrong Cork Company, Lancaster, Pa., a corporation of Pennsylvania

Application August 30, 1949, Serial No. 113,186

8 Claims. (Cl. 73—425.6)

1

This invention relates to a device for sampling fluid materials and is concerned particularly with a device for taking samples of a fluid such as oil from within a container such as a tank car at various locations throughout the depth of the fluid in the car. The invention is particularly useful, for example, in securing samples of oil from a tank car where stratification may have occurred and where it is desired to secure representative samples at various depths in the car, including locations spaced from the bottom thereof or where water or other contaminants may lie at different levels within the body of oil. The device is effective for use in sampling viscous fluids or semisolids such as certain oils which congeal to a semisolid condition when cold, such as China-wood oil. It is also useful in the sampling of powdered materials which are capable of flowing. The term "fluid materials" is used in its broadest sense and is not limited to liquid or semiliquid materials.

It is an object of this invention to provide a sampling device for fluid materials which will be effective for securing a specimen truly representative of any given stratum of the body of material to be sampled at which the sample is secured.

Another object of my invention is to provide a sampling device which will be useful with all fluid materials, including semisolid oils and the like and powdered materials of a fluid nature, as well as with liquid and semiliquid materials.

A further object of the invention is to provide a sampling device in which the sample container may be sealed against the ingress of fluid as the device is moved to its desired location within the body of fluid material to be sampled, may be there opened to receive the sample, and may be sealed against the egress of the sample therefrom or the entrance of contaminants into the container as the device is removed from the body of fluid.

The device of this invention includes a receptacle, preferably in the nature of a cylinder, which is provided with a suction plunger which may be moved within the cylinder to draw the specimen of material within the container through a lower opening in the container. The suction plunger is provided with a pair of valves, one of which closes the opening in the container when the suction plunger is in its lowered position, preventing the ingress of liquid into the container as it is lowered into the desired position within the body of material to be sampled, and the other of which closes the open-

ing in the container when the suction plunger is in an elevated position, and thus prevents the egress of the sample from within the cylinder and eliminates the possibility of contaminants entering the container.

In order that the invention may be readily understood, a preferred embodiment thereof will be described in conjunction with the attached drawing, in which:

10 Figure 1 is a sectional view of the device of the invention, being shown in two parts adjoined by a bracket;

Figure 2 is a sectional view taken along the line of II—II of Figure 1;

15 Figure 3 is a sectional view taken along the line of III—III of Figure 1; and

Figure 4 is an elevational view, partially broken away, showing a valve stem for use in the device.

Referring to Figure 1, the device comprises a 20 receptacle 2 which is in the nature of a hollow cylinder. A suction plunger 3 is movable within the cylinder 2. The cylinder 2 has an upper head 4 bolted thereto and a lower head 5 similarly bolted to the cylinder. The lower cylinder head 5 has a central opening which is provided with a removable valve seat 6 held in place within the cylinder head 5 by a retaining ring 7. The valve seat 6 is provided with two sealing surfaces 8 and 9.

25 The suction plunger 3 is connected to a suction rod 10, the lower end of which is of tubular construction, and there is provided a suction rod extension 11 which extends forwardly beyond the end of the suction rod 10, passing through a central opening in the valve seat 6 and the retaining ring 7. The suction rod extension 11 is pinned to the suction rod 10 by pin 12 and is threaded on its opposite end to receive a valve stem 13. A valve 14 is threaded onto the valve

30 stem 13 and has a sealing surface 15 which when brought into engagement with the sealing surface 9 of the valve seat 6 closes the cylinder 2. It is employed primarily to close the cylinder 2 against the egress of fluid therefrom after a 35 specimen has been drawn therein by the suction plunger, as will be more fully described.

The suction plunger 3 may be formed of two parts 16 and 17 with a resilient suction packing arrangement 18 disposed therebetween. The lower plunger section 17 is provided on its outer end with a valve 19 having a sealing surface 20 which when brought into the position shown in Figure 50 1 with the surface 20 in engagement with the surface 8 seals the cylinder 2 against ingress of liquid into the cylinder. It is used primarily to

close the cylinder 2 to prevent the passage of fluid into the cylinder as the device is passed through the body of fluid to be sampled to the desired level therein for sampling, thus avoiding any contamination of the sample and insuring that it will be truly representative of the stratum in which the device lies at the time the specimen is taken.

From an examination of Figure 1 it will be clear that, when the suction rod is moved to the right from the position shown, the valve 19 will be opened by movement away from the valve seat 6 and the valve 14 will be brought into sealing engagement with the valve seat 6. The suction plunger 3 will move a relatively short distance along the axis of the cylinder 2 and will draw into the cylinder a small specimen of fluid material. The quantity of fluid received in the cylinder 2 upon such movement of the suction plunger 3 will be governed by the distance between the sealing surfaces 15 and 20. The stem 13 shown in Figure 1 is quite short and will be used where only a small specimen is desired. The size of the specimen may be varied by using valve stems 13 of different lengths. Figure 4 shows a valve stem 21 corresponding to the valve stem 13 of Figure 1. It is similar in all respects to stem 13 except that its body is longer. It is provided with a threaded opening 22 which receives the threaded end of the suction rod extension 11. With this stem 21 attached to the suction rod extension 11 in place of the stem 13, the cylinder 2 will be substantially completely filled upon movement of the suction plunger from its lower position with the sealing surface 20 in engagement with the surface 8 to its upper position with the sealing surface 15 in engagement with the sealing surface 9.

A supporting tube 23 is attached to the upper cylinder head 4 by bolts 24. The suction rod 10 is guided in its passage through the upper cylinder head 4 by a sleeve 25 in the nature of an oilless bearing. The portion of the device which will be disposed within the fluid to be sampled is so constructed that the fluid will not enter or escape from the device except through the valved opening in the lower cylinder head upon actuation of the suction plunger. The cylinder 2 is vented to permit the entrance and escape of air as the suction plunger 3 is moved within the cylinder. In the embodiment illustrated the suction rod 10 is provided with an opening 26 near its lower end and another opening 26' near its upper end, and the supporting tube 23 is provided with an opening 27 adjacent its upper end.

The suction rod 10 is coupled to a threaded operating rod 28 by a coupling 29 which has a projection 30 extending within the suction rod 10. A tapered pin 31 passes through the extension 30 and the rod 10 joining the two together. The operating rod 28 is free to rotate within the coupling 29 as indicated by the dotted line in Figure 1. The threaded operating rod 28 is in the nature of a quick-acting screw having thread projections 32 and 33 on diametrically opposite portions of the body thereof, with portions 34 and 35 therebetween being recessed. A cooperating threaded member 36 is fastened to the head of the supporting tube 23 by cap screws 37. The member 36 is provided with spaced screw thread projections 38 and 39 (Figure 2) with intervening recesses 40 and 41 free to receive the projecting threads 32 and 33 of threaded operating rod 28 when the rod is disposed in the position shown in Figure 2. Thus in

moving the suction plunger 3 from its closed position, as shown in Figure 1, to its elevated position, the rod 28 is rotated through about a quarter of a revolution to bring the threads 32 and 33 into the recesses 40 and 41 in the member 36; and the rod 28 is then lifted, drawing the suction plunger upwardly in the cylinder. In order to facilitate rotation and lifting of the rod 28, an operating handle 42 is provided which is secured thereto by a pin 43. In order to lock the suction plunger 3 in position, a locking member 44 similar in construction to the member 36 is provided. The member 44 has an operating handle 45 integral therewith. Upon elevation or lowering of the suction plunger, it may be locked in fixed position by rotating the rod 28 to a position where the threads 32 and 33 are in engagement with the complementary threads 38 and 39 on the member 36 with the appropriate sealing surface 15 or 20 in engagement with the valve seat 6, and the locking member 44 may then be slid along the rod 28 until the members 36 and 44 are in abutting relationship, being then rotated to bring the threads 46 and 47 of the locking member 44 into engagement with the corresponding threads 32 and 33 of the rod 28, locking the suction plunger against displacement.

In order to fix the position of the sampling device, and particularly the lower cylinder head 30 through which the fluid material passes into the cylinder 2 for sampling, the supporting tube 23 is provided with a stop 48 which is slideable on the supporting tube 23 and may be fixed at adjusted locations therealong. In the embodiment illustrated in Figure 1, one half of a clamping band 49 is shown. The opposite half normally overlies the section of the supporting tube 23 which is cut away in Figure 1, and locking bolts (not shown) pass through the openings 50 in the stop 48 to hold the stop in adjusted position on the supporting tube. The arms 51 and 52 on the stop 48 are long enough to span the opening through which the device is inserted into the tank car or other receptacle containing the fluid material to be sampled.

In the operation of the device, a valve stem of desired length is positioned on the suction rod extension 11 dependent upon the quantity of fluid to be taken as a sample. The valve 14 is screwed onto the valve stem, and the operator then locks the suction plunger 3 in its closed position as shown in Figure 1 by manipulation of the threaded operating rod 28 and the locking member 44 in the manner described above. Assuming that the sample is to be taken from a tank car at a depth of four feet from the bottom thereof, the stop 48 will be positioned on the supporting tube 23 and clamped thereagainst so that when the stop 48 lies in engagement with the tank car surrounding the opening through which the device is inserted into the car, the lower cylinder head 5 will be disposed four feet from the bottom of the car. The operator then releases the locking member 44 by disengaging it from threads 33 and 34 and turns the operating handle 42 of the operating rod 28 through about a quarter of a revolution to disengage the threads 32 and 33 from the threads 38 and 39 on the member 36. The operating rod 28 is then lifted to bring the sealing surface 15 of the valve 14 into engagement with the sealing surface 9 of the valve seat 6. The operating rod 28 is next rotated through about a quarter of a revolution to bring the threads 32 and 33 into cooperative relation with the threads 38 and 39 of the member 36, draw-

ing the valve 14 into good sealing relationship with the valve seat 6. The locking member 44 is next moved into abutting relationship with member 36; and the handle 45 is rotated to bring the threads of 46 and 47 of the locking member 44 into engagement with the threads 32 and 33 on the operating rod 28, drawing the locking member 44 into firm locking engagement with the member 36. The device may then be lifted from the tank and the contents of the cylinder 2 discharged by opening the valve 14 through operation of the operating rod 28 or by removal of the valve 14.

In the device of the invention, the container for the specimen is sealed against the ingress of fluid as the device is moved through the fluid to the position at which the specimen for sampling is to be taken. When the valve on the suction plunger is opened, the fluid flows or is drawn into the cylinder as the suction plunger is elevated; and when the desired quantity of fluid has been received in the cylinder, the container is automatically sealed against the egress of fluid from the cylinder or the entrance of any contaminating fluid from other levels within the body through which the container may pass. Thus the specimens secured will be truly representative of the fluid at the level at which sampling is effected. The operator can be certain at all times that his valves are closed by drawing the operating rod for the suction plunger into the threaded member 26 firmly and then locking the plunger in its terminal position.

While I have illustrated and described a preferred embodiment of my invention, it will be understood the same is not limited thereto but may be otherwise embodied and practiced within the scope of the following claims.

I claim:

1. In a sampling device, the combination of a cylindrical container, a suction plunger movable within said container from a lowered position to an elevated position, a cylinder head secured to the bottom of said cylinder, said head having an opening therein, a valve seat disposed within said opening, said seat having conical sealing surfaces on the inner and outer sides thereof and a central opening therein, a conical valve carried by said suction plunger and engageable with said inner sealing surface of said valve seat when said suction plunger is in lowered position, a second conical valve disposed outside of said container and engageable with said outer sealing surface of said valve seat when said suction plunger is in elevated position, a valve stem extending through said central opening in said valve seat and connecting said second valve to said suction plunger for movement therewith, a tube connected to the upper end of said container, an operating rod for moving said suction plunger passing through said tube, and complementary screw threads on said rod and tube for moving said valves selectively into firm sealing engagement with the said valve seat upon relative rotation between said rod and tube.

2. In a sampling device, the combination of a container having an opening in the bottom thereof, a suction plunger movable within said container, a valve disposed within said container for closing said opening when said suction plunger is in one position in said container, a second valve disposed outside of said container for closing said opening when said suction plunger is in another position within said container, means for connecting said valves for coincidental movement

with said suction plunger to provide for the opening of each valve as the other is closing, a tube connected to the upper end of said container, operating means for moving said suction plunger, said operating means passing through said tube, and means carried by said tube for holding said operating means in fixed position with one of said valves closing said opening in the bottom of said container.

10 3. In a sampling device, the combination of a container having an opening in the bottom thereof, a suction plunger movable within said container from a lowered to an elevated position, a valve on the end of said suction plunger for closing said opening when said suction plunger is in lowered position, a second valve disposed outside of said container for closing said opening when said suction plunger is in elevated position, a valve stem connecting said second valve to said suction plunger, a supporting tube connected to said container at the top thereof, an operating rod for said suction plunger extending through said tube, and means carried by said tube and engageable with said operating rod for holding said rod in position with said suction plunger in fixed position with said opening in the bottom of said container sealed by one of said valves.

4. In a sampling device, the combination of claim 3 and locking means carried by said rod and engageable with said rod-holding means carried by said tube for locking said rod in position.

5. In a sampling device, the combination of claim 3 in which the rod has a quick release thread thereon and in which the rod-holding means carried by the tube has a complementary quick release thread therein for interengagement with the quick release thread on the rod.

6. In a sampling device, the combination of claim 3 in which the rod has a quick release thread thereon and in which the rod-holding means carried by the tube has a complementary quick release thread therein and locking means carried by said rod having a quick release thread therein complementary to the quick release thread on said rod, said locking means being engageable with said rod-holding means carried by said tube for locking said rod in position.

7. In a sampling device, a cylindrical container, a cylinder head secured to the bottom of the container and having a central opening therein, a valve seat disposed within said opening, said valve seat having an inner and an outer sealing surface thereon and a central opening therein, means for securing said valve seat to said cylinder head, a suction plunger movable within said container between a lowered and an elevated position, a valve carried by said suction plunger and engageable with said inner sealing surface of said valve seat to close said opening in the bottom of said container when said suction plunger is in lowered position, a valve stem carried by said suction plunger and movable therewith, said valve stem passing through said valve seat, a second valve carried by said valve stem and engageable with said outer sealing surface of said valve seat to close said opening in the bottom of said container when said suction plunger is in elevated position, a second cylinder head secured to the top of said container, said second cylinder head having a central opening therein, a tube sealed to said cylinder head surrounding said opening therein, an operating member connected to said suction plunger, said member passing through said tube, means carried by said tube for holding said operating member and suction plunger.

8. In a sampling device, a cylindrical container, a cylinder head secured to the bottom of the container and having a central opening therein, a valve seat disposed within said opening, said valve seat having an inner and an outer sealing surface thereon and a central opening therein, means for securing said valve seat to said cylinder head, a suction plunger movable within said container between a lowered and an elevated position, a valve carried by said suction plunger and movable therewith, said valve stem passing through said valve seat, a second valve carried by said valve stem and engageable with said outer sealing surface of said valve seat to close said opening in the bottom of said container when said suction plunger is in lowered position, a valve stem carried by said suction plunger and movable therewith, said valve stem passing through said valve seat, a second valve carried by said valve stem and engageable with said outer sealing surface of said valve seat to close said opening in the bottom of said container when said suction plunger is in elevated position, a second cylinder head secured to the top of said container, said second cylinder head having a central opening therein, a tube sealed to said cylinder head surrounding said opening therein, an operating member connected to said suction plunger, said member passing through said tube, means carried by said tube for holding said operating member and suction plunger.

er, in fixed position within said container, with said bottom opening therein sealed by one or the other of said valves, and adjustable stop means carried by said tube for engagement with a receptacle surrounding an opening therein through which the device may be inserted for sampling the contents thereof.

8. In a sampling device, the combination of claim 3 in which said valve stem is removably secured to an operating rod extension connected to said operating rod.

ADDISON W. KELLEY.
